UNITED STATES PATENT OFFICE

167,579

SHOE

John S. MacKinnon, Dorchester, Mass.

Application January 5, 1952, Serial No. 17,953

Term of patent 3½ years

(Cl. D7—7)

To all whom it may concern:

Be it known that I, John S. MacKinnon, a citizen of the United States, residing at Dorchester, in the county of Suffolk and Commonwealth of Massachusetts, have invented a new, original, and ornamental Design for a Shoe, of which the following is a specification, reference being had to the accompanying drawing, forming a part thereof, in which:

Fig. 1 is a plan view of a shoe showing my new design, and

Fig. 2 is a side elevational view of the shoe shown in Fig. 1, the sole portion being shown conventionally in dot and dash lines.

My design for a shoe is characterized by the tapered, initialed tab folded over the outside edge of the vamp near the front as shown.

I claim:

The ornamental design for a shoe, substantially as shown and described.

JOHN S. MACKINNON.
